DOUBLE SPIRAL RATCHET WRENCH

Raymond E. Adams, Quinton, Okla.

Application October 8, 1946, Serial No. 701,943

3 Claims. (Cl. 74—127)

1

This invention relates to a new and improved wrench and more particularly and specifically to a socket wrench of the double spiral ratchet type which has as its primary object the provision of a wrench of this type which is faster and easier to operate than those wrenches of the same type which are now in use.

A further object of this invention is the provision of a ratchet socket wrench of the character described which is durable and lasting in use and which comprises a minimum of working parts which are so formed as to be unlikely to get out of working order.

Still further objects and improvements of this invention will readily appear to those skilled in the art when the following description is read in the light of the accompanying drawings, in which:

Figure 1 is an elevation of the wrench with a portion of the handle broken away and disclosed in longitudinal section, the parts being shown in a partially actuated position for rotation in one direction;

Figure 2 is a longitudinal section through the wrench taken at right angles to Figure 1, the parts being partially actuated for rotation in the opposite direction;

Figure 3 is an enlarged fragmentary transverse section taken substantially on the plane of the line 3—3 of Figure 2;

Figure 4 is a fragmentary elevation showing the ratchet arrangement partly disassembled;

Figure 5 is a fragmentary elevation showing the assembled ratchet arrangement and taken at right angles to Figure 4; and

Figure 6 is a fragmentary elevation partly in longitudinal section of the socket and of the forward end of the wrench.

Referring specifically to the drawing wherein like reference characters indicate like parts throughout, A designates a double spiral grooved shank having a pair of diametrically opposed right hand grooves 30 and a like pair of diametrically opposed left hand grooves 31 as is common in wrenches of this type.

The forward extremity of the shank A terminates in a smooth and substantially cylindrical portion 1 which is formed with a bifurcated free end providing ears 2 which are adapted to pivotally support therebetween the socket member 3 on a suitable pivot 4 extending transversely between the ears. The socket member 3 comprises a body 5, the periphery of which is shaped to conform to and is adapted to engage in the usual socket, not shown, of the object to be turned

2

by the wrench. A cylindrical bore 6 extends transversely through the body 5 and seats therein a latch 7. Latch 7 is seated on a coil spring 8 also positioned in said bore and said spring causes the latch 7 to be normally positioned so as to partially protrude above the surface of the body 5 whereby it is adapted to frictionally engage the socket of the turned member. A set screw 9 is inserted in the opposite end of said bore and countersunk below the surface of the body 5. Such screw allows for the replacement of spring 8. A knurled hand grip 10 which comprises a hollow cylindrical member is adapted to be fitted over the smooth portion 1 of the shank A between longitudinally spaced stops 32 and 33 fixed to such portion of the shank whereby the hand grip provides a relatively rotatable grip at the forward end of the wrench.

A directional control member 11 is fitted on the shank A and comprises an externally toothed spur gear 12 at the rear end of a hub portion 35. The control member 11 is internally bored to have a smooth fit on the smooth surface portion of the shank A intermediate grooves 30, 31 but is provided with a pair of diametrically opposed internally directed cam teeth 34 each of which is adapted to seat in one of the left hand grooves 31 of the shank. A second directional control member 13 is likewise fitted over the shank A. The control member 13 is substantially identical to control member 11 and is provided with an externally toothed spur gear 36 at the forward end of a hub portion 37. The control members 11 and 13 are arranged in end to end relation with the spur gears 36 and 12 juxtaposed. The control member 13 is also provided with a pair of internally directed teeth, not shown, which are the same as the teeth 34 of the member 11 but which engage in the two right hand grooves 30 of the shank.

The rear end of shank A and the control members 11 and 13 are contained in a housing B which is generally cylindrical in form and concentric to the shank A. The forward end of the housing 45 B may be internally threaded, as at 14, to receive the externally threaded hub of a nut 15. The nut 15 has a smooth internal axial bore for a sliding fit on the shank A and the inner end of the hub of the nut provides a seat or stop for the forward end of the hub 35 of the control member 11. A washer 38 may be interposed between the squared portion of the nut and the forward end of the housing B. The housing B adjacent the forward end thereof, is formed to provide there-through a longitudinally directed slot C which is

located to overlie the juxtaposed spur gear portions of the control members 11 and 13. The slot C is normally covered by a closure plate 39 which is arcuate and which is detachably secured to the housing B in any suitable manner as by the fasteners 40. The cover plate 39 is formed to provide a pair of longitudinally directed slots 41 and 42 respectively which are laterally spaced and longitudinally staggered whereby the slot 41 has its rear terminus substantially on the plane separating the two control members 11 and 13 and extends forwardly beyond the region of the spur gear 12 of the control member 11. In like manner the forward end of the slot 42 terminates substantially on the plane separating the control members and its rear end terminates rearwardly of the spur gear 36. Each of the slots 41 and 42 receives the stem 43 of a longitudinally reciprocable clutch member 18. The inner ends of the members 18 are laterally bifurcated, as at 44, Figure 3, whereby to provide a longitudinally extended slot 45 which is adapted to receive a tooth of one of the spur gears 12 or 36. The bifurcated head 44 of each member 18 merges with the shanks 43 to provide a beveled shoulder 46 which is engageable with a side edge 47 of the slot C to prevent withdrawal of the members 18 in a radial direction yet permitting longitudinal sliding relative to the spur gears. It is understood that the slots 41 and 42 in the cover plate 39 have a substantially close fit with the shanks 43 of the members 18 whereby to prevent lateral play of such shanks in such slots. Each member 18 is provided with a head portion 48 adjacent its outer free end. A spring steel saddle 16 is interposed between the heads 48 and the cover plate 39 whereby to maintain the beveled portions 46 in frictional engagement with the side edges 47 of the slot C.

The rear end 20 of the shank A is provided with a washer 19 located inwardly of the free end and which is secured in place by a cotter pin 22 extending transversely through the shank A between the washer 19 and the free end. The washer 19 provides a stop which is adapted to abut the rear side edges of an internal flange 51 of housing B and prevent withdrawal of shank A. The forward side edges of flange 51 substantially abut the rear end of the hub 37 of the control member 13 to maintain controls 11 and 13 properly positioned for a purpose which will be apparent later. The free end 20 of the shank A acts as a seat for the forward end of a plunger 23 which is held under tension concentrically within the housing B by a coil spring 24 which surrounds said plunger concentrically thereof. The rear end of the spring 24 is seated against any suitable nipple or bushing 25 threaded into the rear end of the casing B. A handle 26 is secured to the rear end of the housing B in any suitable manner as by being threaded thereon and such handle is provided with diametrically aligned radially extending openings 27 which are adapted to permit the insertion of a small rod 28 through said handle to facilitate actuation of the wrench.

In operation, one of the control members 11 or 13 is locked against turning movement by reciprocating one of the clutch members 18 towards that end of its slot 41 or 42 which overlies one of the control members 11 or 13. In Figures 2 and 3 a clutch member 18 has been moved into engagement with the control member 11 whereby to lock the same against rotation. The other clutch member 18 is moved to the end

of its slot 42 whereby it is disengaged from the control member 13. The control member 13 is, therefore, free to be rotated by the shank A. Rotation of the shank A is now accomplished by pressing downwardly on the handle 26 whereby the housing B through the engagement of the inwardly directed flange 51 thereof with the upper end of the hub 37 moves control members 11 and 13 downwardly along the shank A. As the control member 13 is not engaged by its clutch member 18, such control member rotates freely on the shank A. However, the control member 11 has its clutch engaged with the teeth of the gear 12 whereby to lock such control member. Thus the internally directed cam teeth 34 which are seated in the left hand grooves 31 cause the shank A to rotate relative to the housing B. In like manner when the other clutch member 18 is engaged with the control member 13 and the control member 11 is disengaged from its clutch member, pressing downward on the handle 26 will cause a reverse rotation of the shank A by virtue of the engagement of the internally directed teeth 34 of the control member 13 with the right hand grooves 30 of the shank.

The spring 24 comprises the driving spring to return the handle 26 and housing B to the Figures 1 and 2 position by projecting the shank A outwardly of the housing B as soon as pressure upon the handle 26 is released.

While I have shown and described what is now thought to be the preferred embodiment of my invention, it is to be understood that the same is susceptible of other forms and expressions. Consequently, I do not limit myself to the precise structure shown and described except as herein-after claimed.

Having thus described and explained this invention, what I claim is:

- 40 1. In a ratchet wrench including a double spiral grooved shank having at least one left hand groove and at least one right hand groove, tool engaging means at one end of said shank, a housing concentrically disposed around the other end of said shank and reciprocably mounted relative thereto; a pair of externally toothed spur gears reciprocable relative to said shank with said housing and concentric to said shank, said gears being positioned in abutting end to end relation on said shank, one of said gears including an internally directed cam tooth slidably seated in said left hand groove, the other gear including an internally directed cam tooth slidably seated in said right hand groove, gear engaging locking means carried by said housing, said locking means being adapted to selectively engage one of said gears to lock the same against rotation with said shank whereby to cause the cam tooth of said locked gear to rotate said shank upon reciprocation of said housing thereon, said locking means comprising separate gear engaging locking members, said housing being formed with a pair of longitudinally staggered, laterally spaced and longitudinally extending slots each 50 in the region of one of said gears, each of said slots extending axially beyond one of said gears, said locking members being each slidably into and out of engagement with its respective gear.
- 55 2. In a ratchet wrench including a double spiral grooved shank having at least one left hand groove and at least one right hand groove, tool engaging means at one end of said shank, a housing concentrically disposed around the other end of said shank and reciprocably mounted relative thereto; a pair of externally 60 toothed spur gears reciprocable relative to said shank with said housing and concentric to said shank, said gears being positioned in abutting end to end relation on said shank, one of said gears including an internally directed cam tooth slidably seated in said left hand groove, the other gear including an internally directed cam tooth slidably seated in said right hand groove, gear engaging locking means carried by said housing, said locking means being adapted to selectively engage one of said gears to lock the same against rotation with said shank whereby to cause the cam tooth of said locked gear to rotate said shank upon reciprocation of said housing thereon, said locking means comprising separate gear engaging locking members, said housing being formed with a pair of longitudinally staggered, laterally spaced and longitudinally extending slots each 65 in the region of one of said gears, each of said slots extending axially beyond one of said gears, said locking members being each slidably into and out of engagement with its respective gear.
- 70 3. In a ratchet wrench including a double spiral grooved shank having at least one left hand groove and at least one right hand groove, tool engaging means at one end of said shank, a housing concentrically disposed around the other end of said shank and reciprocably mounted relative thereto; a pair of externally 75 toothed spur gears reciprocable relative to said shank with said housing and concentric to said shank, said gears being positioned in abutting end to end relation on said shank, one of said gears including an internally directed cam tooth slidably seated in said left hand groove, the other gear including an internally directed cam tooth slidably seated in said right hand groove, gear engaging locking means carried by said housing, said locking means being adapted to selectively engage one of said gears to lock the same against rotation with said shank whereby to cause the cam tooth of said locked gear to rotate said shank upon reciprocation of said housing thereon, said locking means comprising separate gear engaging locking members, said housing being formed with a pair of longitudinally staggered, laterally spaced and longitudinally extending slots each 80 in the region of one of said gears, each of said slots extending axially beyond one of said gears, said locking members being each slidably into and out of engagement with its respective gear.

toothed spur gears reciprocable relative to said shank with said housing and concentric to said shank, said gears being positioned in abutting end to end relation on said shank, one of said gears including an internally directed cam tooth slidably seated in said left hand groove, the other gear including an internally directed cam tooth slidably seated in said right hand groove, gear engaging locking means carried by said housing, said locking means being adapted to selectively engage one of said gears to lock the same against rotation with said shank whereby to cause the cam tooth of said locked gear to rotate said shank upon reciprocation of said housing thereon, said locking means comprising separate gear engaging locking members, said housing being formed with a pair of longitudinally staggered, laterally spaced and longitudinally extending slots each in the region of one of said gears, each of said slots extending axially beyond one of said gears, said locking members being each slidably into and out of engagement with its respective gear, and spring means associated with each locking member for holding the same in a selected position.

3. In a ratchet wrench including a double spiral grooved shank having at least one left hand groove and at least one right hand groove, tool engaging means at one end of said shank, a housing concentrically disposed around the other end of said shank and reciprocably mounted relative thereto; a pair of externally toothed spur gears reciprocable relative to said shank with said housing and concentric to said shank, said gears being positioned in abutting end to end relation on said shank, one of said gears including an internally directed cam tooth slidably seated in said left hand groove, the other gear including an internally directed cam tooth

slidably seated in said right hand groove, gear engaging locking means carried by said housing, said locking means being adapted to selectively engage one of said gears to lock the same against rotation with said shank whereby to cause the cam tooth of said locked gear to rotate said shank upon reciprocation of said housing thereon, said locking means comprising separate gear engaging locking members, said housing being formed with a pair of longitudinally staggered, laterally spaced and longitudinally extending slots each in the region of one of said gears, each of said slots extending axially beyond one of said gears, said locking members being each slidably into and out of engagement with its respective gear, and spring means associated with each locking member for holding the same in a selected position, said locking members each including a stem extending radially outwardly of said housing, a head on the free end of each stem, and said spring means each comprising a leaf spring interposed between each head and the outer surface of said housing.
